UNITED STATES PATENT OFFICE.

ROSE BINNER SCOGNAMILLO, OF NEW YORK, N. Y.

CORSET.

No. 913,921.

Specification of Letters Patent.

Patented March 9, 1909.

Application filed October 17, 1908. Serial No. 288,182.

To all whom it may concern:

Be it known that I, ROSE BINNER SCOGNAMILLO, a citizen of the United States, residing at New York city, borough of Manhattan, county and State of New York, have invented certain new and useful Improvements in Corsets, of which the following is a clear, full, and exact description.

This invention relates to corsets, the object being to provide a corset that is constructed to reduce the hips and thighs. Contrary to the usual hip-reducing corset, my improved corset reduces the hips and thighs by means of a thigh-band, which also reduces the hips, which is preferably integral with the corset proper and which is strapped directly to the thighs. My improved corset differs from the usual hip-reducing corset in the respect that it does not depend entirely upon the hose-supporters to get a downward pull. My improved corset is, however, provided with hose-supporters.

My improved corset effects the result of reducing the hips and thighs by compressing the loose flesh into a smaller space without necessarily subjecting the adjacent organs to any undue pressure which would cause distress. As the flesh of the human body is more or less compressible, I have taken advantage of this fact and constructed my improved corset to compress the flesh about the hips and thighs.

I will now proceed to describe my invention, the novel features of which I will finally claim, reference being had to the accompanying drawing forming part hereof, wherein—

Figure 1 is a front elevation of my improved corset; Fig. 2 is a rear view thereof; Fig. 3 is a diagrammatic face view of one of the members of my improved corset; and Fig. 4 is a fragmentary front view of another form of thigh-bands.

Referring now to the drawing, my improved corset comprises the bust-supporting halves 1 and 2, which are provided with the usual steels 3. Each of the halves 1 and 2 are provided, at the front thereof, with fastening devices adapted to engage each other as at 4 (Fig. 1). The halves 1 and 2 are adjustably secured together at the back by the usual facing 5. The usual form of corset terminates at the lower end, at about the waist line, but my improved corset continues downwardly in the form of thigh-bands 6 and 7. The thigh-bands 6 and 7

are preferably formed integral with the halves 1 and 2, and do not contain any steels, but are pliable members adapted to be drawn tightly against the thighs. The thigh-bands 6 and 7 are each provided with hose-supporters 8 and 9, each of the halves 1 and 2 being also provided with hose-supporters 10 and 11. It may here be stated that to avoid hiding the important features of my corset, the hose-supporters 10 and 11 have been shown as drawn to one side (see full lines Fig. 1), the operative position of said supporters being indicated by dotted lines. As can be seen in Fig. 1, the said halves 1 and 2 are partially severed, as at 12 and 13, the said halves being severed at about the position of the groin, indicated by 14, the purpose being to afford the wearer an easy movement when bending over, also to permit the supporters 10 and 11 to aid in reducing the abdomen.

As can be seen in Figs. 1 and 2, the thigh-bands 6 and 7 almost encompass the thigh and entirely cover the hips, and at the rear of the corset the thigh-bands almost completely cover the buttocks. Each of the halves 1 and 2, at the rear thereof, have attached thereto resilient binding-straps 15, 16 and 17 and 15^a, 16^a and 17^a respectively. At the front of the said halves, the said straps are adapted to engage the tabs 18, 20 and 22 and 19, 21 and 23 respectively, the said straps being provided with buttons 24, and the tabs with sockets 25. Any of the well-known fastening devices can be used. The function of the binding-straps is to draw the thigh-bands tightly against the thighs, thereby compressing the flesh, and also preventing the encompassed muscles from working as the person walks. When the thigh-bands are tightly bound in position against the thighs, they will tend to draw the flesh over the hips downwardly when the wearer stands or walks erect.

It will be seen by the foregoing description that the reducing of the flesh over the hips, and at the thigh portion, of the wearer of my improved corset is accomplished by compressing the flesh by means of a band tightly drawn over the flesh at the said named region, the bands which accomplish the drawing effect being adapted to pass completely around the leg. My improved hip and thigh reducing corset comprises bust-supporting elements provided with flesh-compressing elements at the lower end thereof,

the said compressing elements constituting a thigh-band. The supporters 8, 9, 10 and 11 are for the usual purpose of supporting the hosiery. In Figs. 1 and 2, the clasping members of the supporters have been omitted, but are shown in Fig. 3. I consider it within the scope of my invention to use the hip and thigh reducing portion of my corset without the bust-supporting members.

10 In the form of thigh bandage shown in Fig. 4, the straps 15 are sewed directly to the thigh-bands 6 and 7, at the front thereof, instead of being releasably attached thereto.

Having now described my invention, what 15 I claim and desire to secure by Letters Patent is:

A corset comprising halves adjustably

connected at the rear thereof, and provided with clasping means at the front thereof, each of said halves being provided with a 20 thigh-band integral therewith adapted to cover the hips and a portion of the thighs, said halves being severed adjacent to the 25 groin region of said halves, and binding straps adapted to bind said thigh-bands firmly to the thighs and hips, together with hose-supporters carried by said halves.

Signed at New York city, N. Y., on this 14th day of October, 1908.

ROSE BINNER SCOGNAMILLO.
